UNITED STATES PATENT OFFICE.

HERMAN H. WENTHE, OF CHICAGO, ILLINOIS, ASSIGNOR TO MEYER & WENTHE, OF CHICAGO, ILLINOIS, A COPARTNERSHIP CONSISTING OF GUSTAV A. J. MEYER AND HERMAN H. WENTHE.

COMBINATION SEAL PRESS.

Application filed October 1, 1928. Serial No. 309,587.

My invention relates to portable seal presses adapted to be used by notaries and other officers for embossing seals or impressing legends on documents.

5 Seal presses for such purposes are now commonly used in two types, one being a desk type having a base adapted to seat on a table top when in use, while the other is a hand or pocket type designed to be held 10 free of any support when it is being used. The hand type has the advantages that it can be constructed without a large and consequently heavy base, thus permitting it to be built in a much more compact form and 15 sufficiently light to be carried in a man's coat pocket. On the other hand, the desk type permits the user to have both hands free for shifting the document or papers to the desired position with respect to the die and 20 counter of the press, and also enables the supporting table or desk to resist the thrust so that the press can be used more easily and with less fatigue.

In its general objects, my present invention aims to provide a seal press embodying the advantages of both types and adapted to be used with equal facility after the manner of each of these types—namely, either with the entire seal press held in a single hand of 30 the user and supported entirely by that hand, or with the seal press seated on any horizontal support so that this support will resist the thrust when the press is being operated.

35 Furthermore, my invention aims to provide a simple, light, compact and inexpensive attachment which can readily be affixed to a seal press of the manually held or so-called pocket type for effectively converting this 40 press into a desk type seal press, this attachment being arranged so that it can also be swung to another position for permitting the press to be used when held clear of any support other than the hand of the user. Furthermore, my invention provides an attachment 45 for this purpose which will afford a base portion of considerable spread, and which will be so disposed with respect to the seal press as to be both rigid and effective for resisting the pressure exerted by the user when manipulating the press.

Still further and also more detailed objects will appear from the following speci-

fication and from the accompanying drawings, in which

Fig. 1 is a side elevation of a combination seal press embodying my invention, showing my novel attachment in a position in which it permits the press to be used when freely held in one hand by the user.

Fig. 2 is a bottom view of the same combination press.

Fig. 3 is a side elevation of the same seal press with the attachment swung to a position in which it affords portions of a base 65 for rigidly supporting the press on a table or the like.

Fig. 4 is a rear view, taken from the right hand side of Fig. 3.

Fig. 5 is a bottom view of the combination 70 seal press, with the attachment in its base forming position of Fig. 4.

Fig. 6 is an enlarged and fragmentary 75 transverse section, taken along the line 6—6 of Fig. 5.

Fig. 7 is a fragmentary bottom view showing another shape of the attaching member which makes my seal press convertible.

In the drawings, I am showing my invention as embodied in a seal press of the so-called pocket type having a forked body 1 integral with a lower die plate 2, this lower die plate being disposed in the mouth of the fork on the lower arm 1A of the fork, while the upper die plate 3 is carried by a plunger 4. This plunger is normally raised by a spring (not shown in the drawings) but can be depressed by a lever 5 pivoted to the body on a pivot pin 6, which lever includes a handle 7 extending rearwardly above and beyond the bight of the forked body. The lower arm 1A of the body forms a vertical rib under the lower die plate, and the body has an eye or finger ring 8 behind its bight and in edgewise alinement with this rib 1A, 95 the lower edge of this ring being somewhat above the plane 9 of the desirably straight lower edge of the said rib 1A.

The attachment which permits the above described hand seal press to be used also as 100 a desk press consists primarily of a fork which has the free ends of its arms 10 disposed at opposite sides of the press body 1, these free arm ends being pivoted to the press body (and preferably to the said lower 105 fork arm or rib 1A) by a pivot pin 11 which

extends horizontally through the body transversely of the latter and rearwardly of the lower die plate 2, but forwardly of the finger ring 8. This forked attachment is of such a length that when swung to its forward or inoperative position of Fig. 1, the bight 12 of the fork will extend around the forward end of the rib 1A of the body and the pivot pin 11 is so located that the middle of the bight 12 will underhang the finger ring 8 when the attachment is swung to its operative position of Fig. 3.

Furthermore, the bight 12 of the attachment preferably is laterally widened to a considerable extent beyond the spread which the arms 10 have at their free ends, and this bight is desirably flared in one of its normally vertical directions so that it will afford a wide base when the attachment is in its operative position of Figs. 3 and 4. The widened bight 12 of the attachment is desirably of less height than the rib 1A of the body, so that the lower edge of this rib will be exposed somewhat below my attachment when the latter is in its inoperative position of Fig. 1, and the attachment is so shaped that the lower edge of the bight of the attachment will be in the same plane 9 with the lower edge of the body rib 1A when the attachment is in the operative position of Figs. 3 and 4 in which the finger ring 8 seats on the upper edge of the bight 12. Moreover, the bight 12 of the attachment preferably flares in one direction, namely downwardly when the attachment is in its said operative position, so as to afford a large diametered base in this position without having the bight project unduly below the lower die plate when the attachment is in its inoperative position of Fig. 1.

When the pivoted attachment on the seal press (as thus equipped) is in its inoperative position of Fig. 1, the attachment is effectively out of the way, so that the press can be held in one hand of the user and operated freely by manual pressure exerted between the lever and the bottom of the forked press body.

With the attachment swung to the position of Figs. 3 and 4, the bight 12 will co-operate with the bottom rib 1A of the seal press body in affording a base for firmly supporting the press on any horizontal surface, since this base has a long effective length (reaching from the forward end of the bottom rib 1A to the lower rear edge of the bight 12 of the attachment) and since this bight has a considerable lateral spread. Consequently, an ordinary pocket seal when thus equipped is as stable as a regular desk press when operated after the manner of the latter by downward pressure on the lever. Moreover, when the lever 7 continuously overhangs a portion of the finger ring 8

even with the lever in its raised position (as shown in dotted lines in Fig. 3) the lever swings somewhat rearwardly during its depression, so that the thrust comes directly downward over the widened attachment 70 bight.

To prevent my attachment from swinging by gravity out of the position to which it has been swung, I desirably employ friction means associated with the pivot pin 75 11 to latch the attachment in the adjusted position, and I also desirably construct the pivotal connection so that the pivot pin will not clamp the fork arms of my attachment too tightly against the interposed portion of 80 the body of the seal press. With these objects in mind, I desirably interpose a slightly compressible washer 13 between each lateral face of the rib 1A and one of the two fork arms 12, and form the pin 11 with a 85 shoulder so spaced from the two heads of the pin as to limit the clamping of the said fork arms against the rib, all as shown in Fig. 6.

To prevent twisting strains on this pivotal connection of my attachment to the seal press body, I also desirably form the bight of the attachment of a height greater than this distance between the bottom finger ring 8 and the plane 9 when the attachment is operative (as in Figs. 3 and 6), and form the bight of the attachment with a recess 15 which affords a seat for the adjacent portion of the finger ring, this recess being of 95 such width as to prevent lateral movement 100 of the ring with respect to my attachment.

In practice, this attachment desirably has the flaring portion of its bight extending through an arc of fully three quarters of a circle, and has the largest diameter of this flaring portion not larger than the diameter of the lower die plate 2, thereby affording the desired widespread of the base when the attachment is in its operative position but without having the arcuate flaring portion 110 of the attachment project beyond the lower die plate when the attachment is in its inoperative position.

Since the forked member of my attachment can readily be formed of sheet metal, 115 the entire cost of applying the same to a seal press is quite low, so that my invention provides a convertible seal press at a cost only slightly above that of a regular hand type press. Moreover, my attachment adds 120 so little to the weight as not to affect its desirability in a seal press intended to be carried in a pocket.

However, while I have heretofore described my invention in an embodiment including a flaring arcuate bight on the member which makes the press convertible, a recess in this bight, and friction washers associated with the pivoting of this member, I do not wish to be limited to these or other 130

details of the construction and arrangement thus disclosed. Changes may be obviously made without departing either from the spirit of my invention or from the appended 5 claims. For example, the widened bight of my attachment might be shorter (longitudinally of the press) and without any flare, as shown in Fig. 7. So also, I do not wish to be limited to the application of my invention 10 to seal presses having a ring formation in the manually engageable portion toward which the lever moves during the making of a seal impression, as I am using the term ring here in the broad sense of denoting this 15 manually engageable portion regardless of its shape.

I claim as my invention:

1. A supporting attachment for a hand seal press of the type having a finger ring 20 at its lower rear end and having a lower die plate adjacent to its lower forward end, comprising a forked member having its arms pivoted near their free ends to the press below and behind the said die plate; the 25 forked member being of such a length that its bight will underhang the said die plate when the said member is swung forwardly, and will underhang the finger ring when the said member is swung rearwardly.

2. A seal press supporting attachment as 30 per claim 1, in which the bight of the forked member flares downwardly when the said member is in its rearwardly swung portion.

3. A seal press supporting attachment as 35 per claim 1, in which the bight of the forked member has an edge recess entered by the finger ring when the said member is swung rearwardly.

4. A hand seal press of a lever type, having 40 a longitudinal bottom body rib and having a finger ring underhanging the lever of the press behind the said rib, in combination with a forked member having its arms straddling and pivoted to the said rib; the said 45 member being movable from a forward position in which its bight extends around the forward of the said rib, to a rearward position in which the said bight underhangs the finger ring to serve as a support for the finger ring portion of the seal press.

5. A hand seal press combination as per 50 claim 4, in which the forked member has a laterally widened portion adjacent to its bight, and in which the lower edge of the 55 said widened portion is substantially in a

common plane with the bottom of the said rib when the forked member is disposed in its said rearward position.

6. In a seal press, a frame including in rigid formation a lower die plate, a bottom 60 rib extending rearwardly below the said die plate and terminating rearwardly of the forward edge of the said die plate, and a handle at the lower rear end of the frame in longitudinal alinement with the rib; and a base 65 attachment comprising a forked member having the free ends of its arms disposed at opposite sides of the rib and pivoted to the latter on a horizontal axis; the position of the said axis and the length of the forked 70 member being such that the bight of the said member will underhang the die plate forwardly of the rib when the said member is swung to a forward inoperative position, and that the said bight will underhang and 75 engage the bottom of the said handle when the said member is swung to a rearward operative position.

7. A seal press as per claim 6, in which 80 the forked member has an arcuate bight portion extending through an arc of over 180 degrees and flaring in a direction which is downward when the forked member is in its rearward position, the diameter of the 85 larger end of the flaring bight portion being not greater than that of the said die plate.

8. A seal press as per claim 6, in which 90 the height of the said flaring bight portion is less than the height of the said rib below the lower die plate, so that the said rib will project below the said bight portion when the forked member is swung forwardly into engagement with the bottom of the 95 said die plate.

9. A seal press as per claim 6, in combination 95 with frictionally operative means for retaining the forked member in its inoperative position.

10. A seal press as per claim 6, in combination 100 with frictionally operative means for retaining the forked member in either its operative or its inoperative position, the said means comprising two friction washers associated with the pivoting of the forked member to the rib, each washer being disposed between one lateral face of the rib and one arm of the forked member.

Signed at Chicago, Illinois, September 28th, 1928.
